UNITED STATES PATENT OFFICE.

FRANK R. FISHER AND PROSPER S. ROBBINS, OF ST. LOUIS, MISSOURI;
SAID ROBBINS ASSIGNOR TO SAID FISHER.

CRATE-FASTENER.

SPECIFICATION forming part of Letters Patent No. 373,731, dated November 22, 1887.

Application filed August 25, 1887. Serial No. 247,861. (No model.)

To all whom it may concern:

Be it known that we, FRANK R. FISHER and PROSPER S. ROBBINS, both of the city of St. Louis, in the State of Missouri, have invented a certain new and useful Improvement in Crate-Fasteners, of which the following is a full, clear, and exact description, reference being had to the accompanying drawings, forming part of this specification, and in which—
10 Figure I is a perspective view of a crate provided with our improved fastener. Fig. II is an enlarged detail perspective view, showing part of the slide and part of the upper slat of the central partition. Fig. III is an enlarged detail perspective view of the central slat. Fig. IV is an enlarged detail perspective view of one of the end slats and the slide.

Our invention relates to fastenings for poultry and other crates; and our invention consists in features of novelty hereinafter fully described, and pointed out in the claims.

Referring to the drawings, 1 represents the body of the crate, and 2 the movable slat closing the space through which the birds are removed.

3 represents the upper slat of the central partition, and 4 the top end slats of the crate. These slats 3 and 4 are notched out at 5 to receive the slide 2, as shown.

30 6 represents straps secured to the slats 4, (and 3 also, if desired,) and which hold the slide in the notches 5, but which allow the slide to move endwise, when desired.

8 represents a spring, consisting preferably of a strip of sheet metal secured at its ends to the slide 2 by means of screws 9 and 10. It is bent at 11 and 12 to form shoulders that bear against the opposite sides of the slat 3, when the slide is closed, and which prevent the slide from moving endwise until the shoulders are pressed inward, as shown by dotted lines in Fig. II. As the spring is forced inward,

the portion 13, between the shoulders 11 and 12, enters a recess, 14, in the slide, as shown, thus allowing the spring to act. The natural 45 position of the spring is that shown in full lines in Figs. I and II, and when it is forced into the position shown in dotted lines in Fig. II it will be understood that the slide may be moved endwise. To allow the spring to act 50 freely, the screws 10 pass through a slot, 15, in the spring, allowing this end to move slightly as the spring is compressed, and as it moves outward into using position the inclined portion of the spring from the end toward 55 one of the shoulders will ride against the end of the notch 5 in the cleat 3, and the spring will be automatically compressed, and as soon as the shoulder passes the notch the spring 60 will move outward, holding the slat in place. 60

We claim as our invention—

1. In a crate-fastener, in combination with the slide, the spring 8, having shoulders 11 and 12, and secured to the slide fixedly at one end and movably at the other, substantially 65 as and for the purpose set forth.

2. In a crate-fastener, the combination, with the slide having notch 14, of the spring 8, secured to the slide and having shoulders 11 and 12 and portion 13, substantially as and for the 70 purpose set forth.

3. In a crate-fastener, the combination of the slide, spring 8, secured to the slide at one end by screws 9 and at the other end by screws 10, entering the slot 15, portion 13 on the spring 75 opposite a notch, 14, on the slide, and straps 6, substantially as and for the purpose set forth.

FRANK R. FISHER.
PROSPER S. ROBBINS.

In presence of—
JAS. E. KNIGHT,
JOS. WAHLE.
